A. C. SOULE

WINDOW MOUNTING

Filed Nov. 9, 1921

UNITED STATES PATENT OFFICE.

ARTHUR C. SOULE, OF SAN FRANCISCO, CALIFORNIA, ASSIGNOR TO SIMPLEX WINDOW COMPANY, OF SAN FRANCISCO, CALIFORNIA, A CORPORATION OF CALIFORNIA.

WINDOW MOUNTING.

Application filed November 9, 1921. Serial No. 513,930.

To all whom it may concern:

Be it known that I, ARTHUR C. SOULE, a citizen of the United States, and a resident of the city and county of San Francisco, State of California, have made a new and useful invention—to wit, Improvements in Window Mountings; and I do hereby declare the following to be a full, clear, concise, and exact description of the same.

10 This invention relates more particularly to an operating means for individually or collectively controlling the movement of sashes slidably pivoted in a window frame.

An object of this invention is to produce 15 a sash mounting, capable of being fabricated cheaply and quickly and installed within a window frame with a minimum amount of labor and expense, and in combination therewith, a sash control that will be superior in 20 point of simplicity, inexpensiveness of construction, positiveness of operation, and facility and convenience in use and general efficiency.

A further object of this invention is to 25 provide a sash mounting which will support a sash uniformly and evenly in its various adjustments, which will permit the sash to be reversed within a window opening. A still further object is to provide means, in 30 combination with the sash support, which will permit the sashes to be operated independently or collectively. Other objects and advantages will appear as this description progresses.

35 In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

40 In the accompanying one sheet of drawings:

Fig. 1 is a partial vertical section through a window frame having sashes therein and provided with supporting and operating 45 means constructed in accordance with my invention.

Fig. 2 is a fragmentary elevation of Fig. 1 from the inside.

Fig. 3 is an enlarged detail, in perspective, 50 of a part of a sash, slide shoe and guide way.

Fig. 4 is a cross section taken through Fig. 5 on the line 4—4.

Fig. 5 is a detail side elevation of a portion of the end of a sash with a bracket thereon.

Fig. 6 is an enlarged plan section taken through Fig. 1 on the line 6—6.

Fig. 7 is a plan section taken through Fig. 2 on the line 7—7.

Fig. 8 is an enlarged side elevation illustrating a sash, slide shoe and guide-way.

In the building of school rooms, work shops, offices and the like, where the maximum of light and ventilation is desired, window apertures are provided which will 70

accommodate a plurality of sashes. Where a plurality of sashes are arranged vertically within the window aperture, it is oftentimes difficult to manipulate or operate the sashes

out of reach of the hands of an operator. 75

It is therefore an object of my invention to provide projections extending away from the inner faces of the sashes, to which, may be secured operating bars, extending down-

wardly, to a point where the same will be 80 accessible and easily operated. The type of sash operating means is not designed to be used on ordinary sliding sashes, but particu-

larly in combination with sashes ar- 85

rangeed on a supporting means similar to that described in my Letters Patent, No. 1,072,669, issued September 9, 1913. This

sash support comprises means for pivoting the sashes on opposite sides to slide shoes

frictionally engaging channels or guide- 90

ways mounted vertically on opposite sides of the window frame, to permit swinging of the sashes in the window frame for ven-

tilation. The movement of the sashes is controlled by a system of bars interposed be- 95

tween the sashes and the window frame, to hold the sashes in any fixed position desired against wind pressure or other shifting forces. The pivotal type of sash, without

my improved controlling and operating 100 means thereon, is difficult to control in its various evolutions owing to the shifting of the center of gravity when the sash is moved from the closed or vertical position to the open or horizontal position and reversed, or

restored to the vertical position.

In detail, the construction illustrated in the drawings includes the window framing composed of the sill 1, stool 2, side jambs 3 connected across the top by the lintel 4, and 110

the usual stops 5 or other weather proofing finish, joined in the usual manner to form a rectangular frame or casement.

By the present construction and invention, 5 the sashes and other mountings may be conveniently fabricated and easily installed by mechanics of ordinary skill, with the insurance of perfect operation. This is accomplished by providing channel shaped 10 guide-ways 6 each having an angular extension 7 thereon, adapted to be secured and rigidly fixed in a vertical position on the opposite side jambs 3. Suitable openings 15 8 are provided in the flanged edges 7 through which nails, screws or other fastening media may pass for joining the guide ways to the side jambs 3. The guide ways each preferably consist of a length of flattened metal formed to the desired contour 20 and treated with a suitable weather resisting coating. A stop 5 is secured to the said jambs 3 and covers the flange 7 so as to finish the interior of the window frame in accordance with standard practice. The 25 edge 10 of the guide way 6 is spaced away from the face of the jamb for the purpose to be hereinafter described in detail.

Sashes are adapted to be mounted within the window frame so that the inner faces 30 thereof will lie against the outer exposed faces of the guide ways 6. The sashes are supported within the opening by the support arms 11 pivoted to the opposite sash stiles 12 at or near their centers, on the 35 fixed pivots 13. The opposite ends of the support arms are pivoted at 14 to the slide shoes 15. The slide shoes 15 each consist of a flat metal plate, having a flanged edge 16 thereon, bent at right angles to the main body of the plate, and which flanged edge is adapted to pass within and slidably engage the walls of the channel in the guide way 6. A carrier arm 17 is pivotally connected to a plate 18, secured to the side 40 jamb 3, and pivotally connected at its opposite end, by the pivot 19, to the support arm 11. The end stile 20 of the said sash on opposite sides thereof is provided with plates 21 having integral, flanged projections 22 thereon, extending outwardly away from the outer face of said sash. Slide shoes 23, are provided with flanged ends 24, thereon, slidable within the channels of the guide ways 6 and are adapted to be 45 pivotally connected at the opposite ends, by the pivots 25, to the projections 22 on the end stiles of the said sash. The flanged ends 16 and 24 of the respective slide shoes, 15 and 23, are of a thickness slightly less than the inner width of the guide way channel whereby said shoes will slide vertically within said channel. By pivotally securing 50 an end of a sash to the slide shoes 23 and pivotally securing a support arm 11 to each 55 slide shoe 15, and to each carrier arm 17,

which is secured to a relatively stationary surface, the weight of the said sash and supporting mechanism tends to twist or cramp the flanged ends 16 and 24 of the slide shoes 15 and 23 within the channel 70 of the guide way, and to cause friction between the said flanged ends and the walls of the channel at the points of contact. The weight of the sash acting through the slide shoes causes sufficient friction within the channel 75 so that said sash will stay placed at any angle desired. The twisting or warping action of the slide shoes within the channel is obtained by placing the pivots connecting said slide shoes to said sash away 80 from the outer face of said sash. It will be obvious that the farther away the pivots 25 are spaced from the face of the sash, the greater will be the tendency to twist the flange of the slide shoe within the channel, 85 and incidentally, placing the pivot 25 away from the face of the sash serves a secondary purpose in that it aids the leverage necessary in opening or moving a sash from the closed or vertical position to any angular 90 position.

The construction thus far described with reference, to the upper sash, applies equally as well to any number of sashes arranged to operate in conjunction therewith. Sashes 95 thus mounted operate substantially as follows. The meeting rails 27 and 28 of the upper and lower sashes, are suitably shaped, in the usual manner to exclude weather and to rest one within the other so that when the adjacent sashes are closed they present an even plane. With the sashes thus assembled and installed and presumed to be in the fully closed position, the first action to manually open said sashes is to push 100 outwardly on the lower rail of either of said sashes. This causes the sash to swing outward on its pivots 25 causing the shoes 23 to slide downwardly within the channel 6, releasing the meeting rail 27 from the 110 rail 28, and the sash resuming any angle desired. In a similar manner, the remaining sash can also be placed at any desired angle. The pivot shoes 23 descend as the 115 sash approaches the horizontal plane, and when fully reversed the sash presents its outer surface to the interior of the room to facilitate washing. The lower slide shoe 15 of the support arm 11 rises under the influence of the fulcrum 19 as the sash opens. The carrier arm 17 being pivotally fixed at 120 one end to the stationary surface and pivotally connected at its opposite end to the support arm 11, performs a valuable function in controlling the sash, as it transforms what would be a simple pivot action at the point 14, into a slide action accommodated by the slide shoe 15, and causes a twisting or pinching action between said slide shoe and 125 channel which must be overcome before the 130

sash can move. The sash is maintained at the desired angle, in addition, by the slide shoe which through the pivotal connection with the spaced plate pivots 25, tends to 5 twist or pinch to hold the sash in any set position yet capable of easy movement at the will of the operator.

The manual method of opening the sashes applies particularly to those sashes within 10 reach of the hands of an operator but it becomes necessary to have an operating mechanism for controlling the movement of those sashes which are out of the reach of the hands of an operator. To open and 15 close the higher positioned sashes, I have provided a pressed metal bracket 30 which is adapted to be secured to the inner face of the sash on one of the side stiles adjacent the pivoted upper end of said sash. The 20 bracket 30 is secured to the said sash by screws, nails or other appropriate media and the free end 31 of the said bracket extends away from the face of the sash for a distance sufficient to clear the casing and in- 25 terior trim about the window frame.

In Fig. 1, I have shown the upper sashes provided with the brackets 39 and with operating means connected therewith, comprising a pair of bars 32 and 33, placed side 30 by side, and held in a vertical position within the clasps 34, secured to the interior of the window jamb at spaced intervals. The controlling bars 32 and 33 are pivotally connected to the ends 31 of the brackets 30, 35 by connecting arms 35 and 36, respectively. The control bars are of sufficient length to be slidably guided within the clasps 34 when the respective sashes are in either the normally closed or fully opened positions. The 40 lower end of the control bar 32 is provided with an angular projection 37 thereon. A handle element 39 is pivoted to the window casing at 40 by a friction adjustment pivot 41. The handle is slotted intermediate its 45 ends as at 42 to receive a pivot pin 43 fixed in the projection 37. The end of the pivot pin 43, projecting through the slot in the handle 39, is peaned over so as to maintain said pin and handle in slidable relationship. 50 It will be obvious that angular movement of the handle 39 will elevate or lower the bar 32 accordingly. In order that the bars 32 and 33 may be elevated or lowered in unison, I have provided a detachable engagement 55 between the respective bars consisting of a resilient spring finger 38 fixed at 44 to the bar 32. The free end of the spring member 38 is provided with an opening 38' therein which is adapted to receive a projection 33', 60 fixed on the face of the bar 33. A finger grip 47 is provided on the end of the spring member 38 to facilitate in engaging or disengaging said spring element with or from the projection 33'. By disengaging the 65 spring latch 38 from the projection 33', it

is possible to operate the upper sash individually or by connecting the bars 32 and 33 together, the sashes may be thus operated collectively. It will be obvious that the individual or collective movement of the 70 controlling bars 32 and 33 will be transmitted through the connecting arms 35 and 36 to the respective sashes, whereby said sashes may be moved either collectively or individually. It is thus possible to move 75 the sashes from the normal closed position to a horizontal position, but where it is desired to completely reverse sash, the connecting arms 35 and 36 would be disconnected from the bars 32 and 33 by removing 80 the pivots 45 and the reversal of the sash made manually.

In practice any number of sashes may be assembled in a single casement frame and any or all of the sashes provided with the 85 particular type of operating means according to the desires of the operator, it being preferable however, that only those sashes out of the reach of the hands of an operator be fitted with a sash operating 90 means. In Fig. 1, a combination of three sashes is shown, with a lower sash arranged so as to be directly operated by the hands of an operator and the upper sashes provided with the interposed operating mech- 95 anism. I do not wish to be understood as limiting this invention to the specific form of sash control, as many forms covered by patents in my name and others may be interposed between the sashes and casing. 100

Particular attention is to be called to the distance between, the pivotal axis of the pivot 25 and the sliding axis of the flanged end 24 of the slide shoe within the channel of the guide-way 6. The axis of the pivot 105 25, under normally perfect conditions, is adapted to move vertically on an imaginary line substantially parallel with a central sliding axis passing through the channel guide way. But the pivoting of a sash or 110 other weight at 25, to the slide shoe 23 having its flanged end 24 in the channel guide-way tends to cause a friction between the flanged edge 24 and side walls of the channel. The force exerted in changing the 115 angular position of the sash is sufficient to overcome the aforementioned friction, and to permit placing the sash at any desired angle. The practice of arranging the sash and pivot 25 as described is utilized to good 120 advantage by extending the bracket 30 away from the opposite face of the said sash, thereby increasing or multiplying the leverage necessary for operating and controlling the movement of the said sash. The movement of said sash control in combination with the pivoted and sliding sash permits the sash to be placed in any desirable angle without the necessity of "slamming" or using undue force in manipulating the same. 125

In adapting this invention to steel construction and to meet other special conditions, modifications within the purview of the invention are available to those skilled in the art and practice of this invention.

In order to exclude the weather, weather strips 46 are provided on the stiles 12 of the sash which extend from a point adjacent the bottom rail 27 to the upper rail 10 28 of the said sash, being cut away only sufficiently so as to permit the slide shoe 23 to clear.

Having thus described this invention what I claim and desire to secure by Letters Patent is:—

1. A window construction including a frame having guides on the opposite sides thereof; sashes in said frame; brackets on said sashes projecting beyond a face thereof; shoes slidably engaging said guides and pivotally connected to said brackets beyond the face of the sash and supporting means interposed between said sashes and frame.

2. A window construction including a frame having guides on the opposite sides thereof; sashes in said frame; brackets on said sashes projecting beyond a face thereof; shoes of greater width than the thickness of said sash slidably engaging said guides beyond one face of said sash and pivotally connected to said brackets beyond the opposite face of said sash; and supporting means slidably and pivotally interposed between said sashes and frame.

3. A window construction including a frame having guides on the opposite sides thereof; sashes in said frame; brackets on said sashes projecting beyond a face thereof; shoes slidably engaging said guides and pivotally connected to said brackets beyond the face of the sash and supporting means interposed between said sashes and frame; and means connected to said sashes for operating the same individually or collectively.

4. A window construction including a frame having guides on the opposite sides thereof; sashes in said frame; brackets on said sashes projecting beyond a face thereof; shoes of greater width than the thickness of said sash slidably engaging said guides beyond one face of said sash and pivotally connected to said brackets beyond the opposite face of said sash; and supporting means interposed between said sashes and frame; and means connected to said sashes for operating the same individually or collectively.

5. A window construction including a frame; guides on opposite sides of said frame; sashes in said frame; slide shoes wider than the thickness of said sashes slidably engaging said guides beyond one face of said sashes and pivotally connected to said sashes beyond the opposite face there-

of; and a supporting means pivoted to said sashes and slidably and pivotally related to said guides and frame.

6. A window construction including a frame having channel guides thereon; sashes in said frame; brackets on said sashes projecting beyond the face thereof; shoes slidably engaging said guides and pivotally connected to said brackets beyond the face of said sash; and supporting means pivoted to said sashes and slidably and pivotally related to said channel guides and frame.

7. A window construction including a frame having channel guides thereon; sashes in said frame; brackets on said sashes projecting beyond the face thereof; shoes slidably engaging said channel guides and pivotally connected to said brackets beyond the face of said sashes; supporting means pivoted to said sashes and slidably and pivotally related to said channel guides and frame; and lateral projections on the faces of said sashes for operating the same.

8. A window construction including a frame having channel guides therein; shoes slidably engaging said channel guides having projections thereon; sashes having brackets thereon, said brackets being pivoted to said projections, supporting means pivoted to said sashes and slidably and pivotally related to said channel guides and frame; and means on said sashes for operating said sashes independently or collectively.

9. A window construction including a frame having channel guides therein; sashes in said frame; brackets on said sashes projecting beyond the face thereof; shoes slidably engaging said channel guides and pivotally connected to said brackets beyond the faces of said sashes; supporting means pivoted to said sashes and slidably and pivotally related to said channel guides and frame; and means connected to said sashes for operating the same independently or collectively.

10. A window construction including a frame having channel guides therein; shoes slidably engaging said channel guides and having projections thereon; sashes, having brackets thereon pivoted to said projections beyond the outer faces of said sashes; supporting means pivoted to said sashes and slidably and pivotally related to said channel guides and frame; brackets, secured to the inner faces of said sashes and control bars pivoted to said brackets to move said sashes.

In testimony whereof, I have hereunto set my hand at San Francisco, California, this 31st day of October, 1921.

ARTHUR C. SOULE.

In presence of—

LINCOLN V. JOHNSON.
